UNITED STATES PATENT OFFICE.

EWALD KARRENBERG, OF CASSEL, GERMANY.

SAFETY DEVICE FOR DOORS.

Application filed February 10, 1921. Serial No. 444,084.

To all whom it may concern:

Be it known that I, EWALD KARRENBERG, a citizen of the German Republic, residing at Cassel, Germany, have invented certain new and useful Improvements in Safety Devices for Doors, of which the following is a specification.

Safety devices for doors are known which comprise a nose arranged at the edge of the door adapted to engage with the guide slot of a locking arm pivotally fixed to the door frame. Devices of this type present the inconvenience that they are not ready particularly when the house or flat is being left.

This inconvenience is avoided according to this invention by providing an angle arm pivotally mounted upon the door frame which forces the locking arm to adopt the locking position when the door is being shut, this locking arm being adapted to be pushed back from the outside with the aid of a key. When the door is being locked the parts which have been displaced by the key return to their normal positions.

In order that the invention may be clearly understood, I shall proceed to describe the same with reference to the accompanying drawings, wherein:

Fig. 1 shows in perspective view the improved device in position ready for working.

Fig. 2 is a section on line A—B of Fig. 5.

Fig. 3 is a similar view as shown in Fig. 2 the device being represented in the position which the parts assume when the device has been unlocked before the door is opened.

Fig. 4 shows in a similar view the device unlocked from the outside by means of a key, the locking arm being turned back and the door being opened, the several parts being shown in different positions.

Fig. 5 is a side elevation of the device in position ready for working.

Fig. 6 shows the interior of the lock in elevation, the outer cover plate (39) being removed.

In connection with the rabbet 20 of the door 5 a piece 22 presenting a nose 4 and further a piece 13 which is twice bent at right angles are fixed upon the base plate 21. A base plate 23 fixed to the door frame 1 carries a second plate 24. Upon this plate 24 a bracket 25 is provided in which a vertical axle 33 for the locking arm 2 is located which has a longitudinal slot 3. The slot

3 which serves to guide and interlock with the nose 4 is inclined towards the left as shown in Figure 1 and has a rectangular enlargement at the right hand end designed to permit the passage through of the nose 4. Two guide faces 26, 27 projecting from the said enlargement serve to guide the upper and lower projecting parts of said nose 4 upon the locking edges when the locking arm 2 is being moved by the opening of the door.

The door releasing position of arm 2 is shown in Fig. 3. In order to return the locking arm 2 automatically from the position shown in Fig. 3 into the operative position shown in Fig. 2 a helical spring 28 is provided which is wound around a pin 29 and bears with its upper end against the supporting plate 30 of a bracket 31 fixed upon the base plate 23, and with its lower end against a collar 32 on the pin 29 which is freely rotatable and longitudinally displaceable in the plate 30. This pin 29 rests with its lower point upon the axle 33 of the locking arm 2. The upper arm of the two fork-shaped arms 34, 35 which embrace the bracket 25 is undercut upon its lower surface that is to say it is provided with an inclined surface 36. The upper contacting surface of the bracket 25 has corresponding incline, as shown in Fig. 1, so that the spring 28 acts to swing arm 2 to the operative position shown in Fig. 2 when the incline on the arm and bracket begin to register. Arm 2 will remain in inoperative position when swung far enough to the right to bring its incline 36 upon the level surface of bracket 25 as shown in Fig. 4.

An angle lever, 6, 7 mounted upon the bracket 25 serves for starting the movement of the locking arm to operative or locking position by bringing the above mentioned inclines into registration (Fig. 1,) the arm 7 of said lever being turned by the rabbet 20 behind which the free end of said arm engages, the other arm 6 of said angle lever being bent so that its end reaches into close proximity with the locking arm 2. When the door is being opened and the locking arm 2 is pushed back the angle lever 6, 7 is brought into the proper position for renewed operation as shown in Fig. 4.

After the door has been closed and locked the locking arm 2 can be disengaged from the nose 4 mounted upon the rabbet 20

through the insertion of a key from the outside. For this purpose a two-armed lever 8, 16 is provided whose arm 8 bears against the locking arm 2 when the same is in its locking position (Fig. 2) the other arm 16 of the lever engaging with a key operated actuating plate 38 which may be of any convenient construction.

In the form of construction illustrated it is supposed that the key inserted into the key pipe 9 of the lock operates the tumblers 10 when it is being turned in clockwise direction (Fig. 6) in order to make the lever 8, 16 swing around its pivot 11. The directions of movement which will be hereinafter described relate also to Fig. 6. For Figures 1 to 4 the opposite directions are to be considered.

The key pushed into the key pipe 9 over the pin 40 moves, when being turned, the actuating plate 38 to the right against the action of the spring 42 as it engages with the indentation 41 of said bolt, lifting at the same time the pivoted tumblers 10 off the pin 43 mounted upon the actuating plate 38 so that the pin 43 is allowed to move in slots 44 of the tumblers. The tumblers are pressed into locking position by the springs 45 which are fixed at 46 each to one of the tumblers, bearing against a pipe 47. If therefore the actuating plate 38 moves to the right in consequence of the rotation of the key in the direction mentioned, the pin 43 moves in the slotted arm 44 without engaging with a notch. As soon as the actuating plate reaches its extreme right hand position, the end 15 of a lever 49, 50 which is influenced by a spring 12 (Fig. 5) and which is adapted to pivot around 48, grips behind the notch 51 of the actuating plate 38 whereby the same is retained. The actuating plate 38 is guided by two rectangular slots 52, 53 with which engage pins 54, 55 of corresponding shape which are rigidly connected with the plate 23.

The free end 56 of the lever arm 50 (Fig. 5) is forked and carries a piece 57 adapted to pivot around the axle 14, said piece being provided with a nose 58 shown in the drawing as extending upwardly and provided at its lower end with a curve 59 and with a straight surface 60. The part of arm 50 which is situated between the fork-shaped arm 56 is formed so that when it presses against the surface 60 the piece 57 can turn around the axle 14 only till the nose 58 buts against the shoulder of said part of arm 50 to drop back into its former position by its own weight (Fig. 5).

When the parts are in the working position shown in Figs. 1 and 2 or when the door is being locked and secured, the nose 4 will move in slot 3, when the door is being opened, up to the left hand end of said slot preventing thus the further opening of the

door. If however the door has to be opened completely the locking arm 2 is brought by hand into the position shown in Fig. 4, the piece 13 butting against the surface 60 (Fig. 5) so that the piece 57 is turned and allows the unimpeded opening of the door. When the door is being closed, the rabbet 20 strikes against the lever arm 7 and makes thus the lever 7, 6 turn. The end 37 of said lever makes the locking arm 2 oscillate until the 75 inclines on the arm 2 and bracket 25 begin to register when the swinging of arm 2 is completed by the spring 28. The piece 13 comes in contact with the curved surface 59 when the door is being closed and lifts the 80 lever arm 50, remaining however without effect as at the opening of the door from the inside the actuating plate 38 remains in its position of rest.

If now the secured door has to be opened 85 from the outside, the actuating plate 38 is moved towards the right (Fig. 6) whereby the end 15 is being secured. The actuating plate 38 moves through the intermediary of the lever 16, 8, the locking arm 2 into the 90 position Fig. 3 so that the door can be opened. When the door is being closed the piece 13 presses against the surface 59 and releases the actuating plate 38 which is now driven into the position of rest through the 95 action of the spring 42.

I claim:—

1. A safety device for doors comprising in combination a locking arm connected with the door frame, means for moving said locking arm out of its locking position by means of a key inserted in the lock from the outside, a two-armed lever adapted to operate with one arm said locking arm, and an actuating plate of the door lock having a slot 105 with which the other arm of said two-armed lever engages.

2. A safety device for doors comprising in combination a locking arm connected with the door frame, means for moving said locking arm out of its locking position by means of a key inserted in the lock from the outside, said means comprising a two-armed lever adapted to operate with one arm said locking arm, and a key operated actuating plate of the door lock having a slot with which the other arm of said two-armed lever engages, a spring influenced lever automatically retaining said actuating plate in operative position and a piece fixed to the door 110 and designed to act upon said spring influenced lever when the door is being closed to release said actuating plate.

In testimony whereof I affix my signature in presence of two witnesses.

EWALD KARRENBERG.
